UNITED STATES PATENT OFFICE.

CHARLES H. REID, OF DANBURY, CONNECTICUT.

HAT-POUNCING MACHINE.

SPECIFICATION forming part of Letters Patent No. 662,821, dated November 27, 1900.

Application filed May 10, 1899. Renewed August 2, 1900. Serial No. 25,705. (No model.)

To all whom it may concern:

Be it known that I, CHARLES H. REID, a citizen of the United States, residing at Danbury, in the county of Fairfield and State of Connecticut, have invented new and useful Improvements in Hat-Pouncing Machines, of which the following is a specification.

My invention relates to machines for pouncing hats, and has for one of its objects to provide means for imparting an irregular motion to a hat-support, so as to subject the flat or substantially flat sides of an oblong hat-body to the action of a pouncer to a greater extent than the round ends thereof, and thereby insure the thorough pouncing of both sides and ends and avoid excessive pouncing or wearing away of the fibers of the latter.

Another object is to provide means whereby an irregular motion or a regular and comparatively fast motion may be imparted to the hat-support at the will of the operator, the regular and comparatively fast motion being designed for use in "slicking" hats to facilitate such operation and being also designed to be used to advantage in the pouncing of round hats as well as in the pouncing of the tips of oblong hats.

Another object is to provide a pouncer movable up the side of a hat to the tip thereof and means for imparting a steady and uniform working motion to said pouncer incident to its movement up the hat and in its various positions with respect to the same.

Other advantageous features of my invention will be fully understood from the following description and claims when taken in conjunction with the accompanying drawings, in which—

Figure 1 is a side elevation of my improved machine. Fig. 2 is a plan view of the machine. Fig. 3 is an enlarged section taken through the pad-body of the pouncer and the actuating-rod thereof. Fig. 4 is an enlarged section taken through the axis of the swinging T-lever with said lever and the parts carried thereby in their lowermost positions. Fig. 5 is an enlarged detail section taken in the plane indicated by line 5 of Fig. 2 and showing the oscillatory arm and its appurtenances. Fig. 6 is a detail perspective view of the drive-shaft from which motion is transmitted to the pad-body of the pouncer. Figs.

7 and 8 are detail perspective views of the sleeves employed on the oscillatory arm shown in Fig. 5. Fig. 9 is an enlarged section 55 illustrating the connection of the pouncing-frame or outer lever of a series to the swinging T-lever. Fig. 10 is a longitudinal central section of the machine with some of the parts partially broken away. Figs. 11 and 12 are 60 sections taken in the planes indicated by lines 11 11 and 12 12, respectively, of Fig. 10. Fig. 13 is a detail view illustrating certain gearing embraced in the machine. Figs. 14 and 15 are detail transverse sections illustrating parts of said gearing. Figs. 16, 17, and 18 are enlarged sections taken in the planes indicated by lines 16 16, 17 17, and 18 18, respectively, of Fig. 10. Fig. 19 is a perspective view of a link for transmitting motion from one gear-wheel to another. Fig. 20 is a similar view of one of the gear-wheels to which the link is connected. Fig. 21 is a perspective view of a key and the slide to which the same is connected. Fig. 22 is an enlarged 75 diagrammatic view illustrating the operation of a portion of the gearing.

In the said drawings similar letters designate corresponding parts in all of the several views.

The machine constituting the preferred embodiment of my present invention embraces much that is common to the hat-ironing machine disclosed in my Letters Patent No. 547,131, of October 1, 1895; but for the sake 85 of imparting a full, clear, and exact understanding of the present invention I will describe the machine as a whole.

A is a framework having boxes B, in which is journaled a hollow shaft C. On the inner 90 end of this shaft is an oblong hat support or block D, the proper position of which is determined by a dowel-pin a, adjustably secured to a head b on the shaft and arranged in a socket c in the block for a purpose presently described. The hat support or block is secured on the shaft by means of any suitable or ordinary chuck operated by a hand-lever d, and as it is not necessary to describe this chuck I will merely state that the hat 100 support or block is secured to the shaft, so as to revolve therewith.

E is the inner lever of a series, which is pivotally connected adjacent to one of its ends

to the frame A, and F is a short shaft journaled in the lever and bearing a worm-wheel G and a crank H, both of which are fixed to it. The crank extends in rear of the shaft F and is weighted, as indicated by e, for a purpose presently pointed out.

I is a pin extending from the frame and having for its purpose to support the lever E when the latter is dropped.

10 J is a dog pivoted in lever E, and f is a spring between the tail of said dog and the lever, whereby the nose on the dog is normally depressed. When the lever E is raised to its uppermost position, the dog will spring into 15 a seat g in the frame, and thereby secure the lever in such position.

K is a trip secured on the wheel G and having for its purpose to dislodge the dog from the seat g, and thereby permit the lever E to 20 drop upon the pin I.

L is a bell-crank lever fulcrumed on frame A and connected by a link h with the lever E, so as to enable the attendant to conveniently raise the lever E and its appurte- 25 nances.

M is a bracket connected to frame A and having a box i, and N is a T-lever, which is the inner one of the series and has a lateral sleeve j at the inner end of its head, journaled 30 in said box.

35 P is a link interposed between and connecting the forward arm of the crank H and the stem of the T-lever, so as to impart motion from said crank as it revolves to the T-lever, causing the latter to rock vertically on its fulcrum. At the outer end of its head the T-lever has a lateral box k, (see Fig. 9,) which extends in an opposite direction to the box or sleeve j, as shown. In said box k is journaled a rock-shaft l, and on the opposite ends 40 of said shaft are fixed arms m n, which, in conjunction with a cross-rod p, constitute a lever or pouncer frame Q. The rod p may be connected to the arms m n in any suitable manner; but I prefer to secure it as best 45 shown in Fig. 9—that is, in a sleeve m' of arm m by a set-screw m² and in a split portion n' of the arm n by a clamping-bolt n². The arm m terminates at its lower end in a toe R, (see 50 Fig. 1,) which has for its purpose to engage a stop q on the T-lever, and thereby limit the outward movement of the pouncer-frame.

55 S is a pouncer, which is preferably of the construction shown, although it may be of any other construction suitable for use in the present machine. The construction of pouncer illustrated forms the subject-matter of my contemporary application of even date here- with, Serial No. 716,233, and need not there- 60 fore be described herein except to say that it comprises a body-plate n³, to which is connected a yielding support or resilient plate n⁴, having a clamp n⁵, by which it is fixed on the rod p of frame Q, arms n⁶, pivotally connected to the body-plate n³, a rod n⁷, suitably connected with the arms, so as to swing there- 65 with, a pad-body made up of end blocks n⁸,

loosely mounted on the rod n⁷, and rods n⁹, arranged side by side between the end blocks, pad-supporting plates n¹⁰, loosely mounted 70 on the rods n⁹, a pad n¹¹, of hair or other suitable material, arranged on the plates n¹⁰, clips r, fixed by set-screws s on the end blocks n⁸, and a piece of sandpaper or other pouncing material t, secured by the clips r over the 75 pad n¹¹. The sandpaper is preferably supplied from a roll u, mounted in a support v, rising from the rod p, and is held against undue unwinding from the roll by a suitable tension device. From this it follows that 80 when it is necessary to replace the portion of paper on the pouncer-pad with a fresh portion the operator has but to loosen the set-screws s, draw the paper through the clips r to the extent necessary, again tighten the 85 screws s, and tear off the deteriorated portion of paper.

By virtue of the pouncer having a resilient or yielding support n⁴ and also having its pad-body mounted so as to rock on the rod n⁷ and 90 its pad resting on rock-plates n¹⁰, whereby it is enabled to cave at its longitudinal center, it will be seen that the said pouncer is enabled at all times to accommodate itself to the contour of a hat, which conduces materially to the thorough pouncing of the same. It will also be observed that by virtue of the rod n⁷, on which the pad-body is mounted, being connected to the swinging arms n⁶ the pad-body and pad will be caused to describe 95 an arc of a circle when the rod n⁷ is moved endwise by means presently described. Such circular movement of the pouncing is highly desirable, since it enables the pad to cover a greater surface than if merely reciprocated, 100 and thereby facilitates the pouncing operation.

105 For the reasons enumerated I prefer to employ the pouncer illustrated in the machine constituting my present invention; but de- 110 scribe it distinctly understood that I do not confine myself to said pouncer, as any other suitable pouncer may be used in the machine.

T is a rod adjustably fixed to and rising from the bracket M; U, an arm adjustably 115 fixed on and extending horizontally from the rod; V, a pulley carried by a box W, adjustable on the arm U; X, a weight, and Y a chain or cord connecting the weight and pouncer-frame Q and taking over the pulley V. The 120 pulley V is adjustably supported by the devices mentioned in order that the weight X and chain Y may be so disposed as not to interfere with the movements of other parts of the machine.

125 The operation of the parts of my improved machine thus far described is as follows: The shaft C being rotated by means presently described to revolve the block D and the lever E having been raised through the medium of lever L to place the worm-wheel G in engagement with a worm Z, fixed on shaft C, and cause the dog J to take into its seat g in frame A, said worm-wheel will revolve in the direc-

tion indicated by arrow. (See Fig. 1.) The crank H, turning with the worm-wheel, will, through the medium of the link P, draw the T-lever N downward, and thereby cause the 5 pouncer S to travel from its initial position (shown in Fig. 10) up the body of the hat toward the tip, the pouncer meanwhile accommodating itself to the curvature or contour of the hat. The chain or cord Y is of such 10 length that during the travel of the pouncer S up the body of the hat the weight X rests on the base supporting the machine, and consequently exerts no pressure on the pouncer-frame Q. When, however, the pouncer 15 reaches the tip of the hat, the weight has been lifted from the base, and hence operates to hold the pouncer to its work and overcomes any tendency of the pouncer-frame and pouncer to fall away from the hat when the 20 pouncer is operating against the tip of the latter. When the pouncer has completed its operations against the tip of the hat, the trip K will dislodge the dog J from its seat g in frame A, as before described, and the lever 25 E will drop and rest upon stop I, as shown by dotted lines in Fig. 10, thus disengaging the worm-wheel G from the worm Z. Immediately subsequent to the disengagement of the worm-wheel from the worm the T-lever N 30 will fall and the pouncer-frame Q will topple backward until the toe R engages stop q, thus carrying the pouncer away from the hat and placing the machine out of operation. The pouncing of the hat being automatic and the machine being thrown out of operation at the 35 completion thereof, it follows that a single operator is enabled to attend to several machines. In restoring the pouncer and other parts from their fallen position to the initial 40 position (shown in Fig. 10) the operator simply grasps the box k or any other suitable part of the T-lever N and raises the parts, this being accomplished with very little effort, owing to the fact that the weight e of 45 the crank H assists in the operation.

In order to transmit a steady and uniform working motion to the pouncing-pad in its various positions, I provide the mechanism best shown in Figs. 2 to 8 of the drawings. 50 A' is the drive-shaft of this mechanism. Said shaft comprises an inner portion a', journaled in the sleeve j of T-lever N and forming the pivot of said lever, an intermediate diametrically-enlarged portion b', having an oblique 55 outer face c', and an outer portion d', arranged off the center of the portion a' and enlargement b' and disposed at right angles or perpendicular to the oblique face c' of the latter. On the enlargement b' of the shaft A' 60 is a hand-wheel e', which is shown as formed separately from and shrunk on the enlargement, although it is obvious that it might form an integral part of said enlargement, if desired. The shaft A' is designed to be rotated by a suitable motor (not shown) through 65 the medium of a band f', which passes around the wheel e' and over idler-pulleys g', as

shown by dotted lines in Fig. 1, in order not to interfere with moving parts of the machine.

B' is a sleeve loosely mounted on the portion 70 d' of shaft A' and held in position by a disk h' or other suitable means. This sleeve B' is provided with a lateral arm C', which by reason of the disposition of the portion d' of shaft A' and the loose arrangement of the 75 sleeve on said portion d' is adapted to oscillate when the shaft is rotated. Said arm C' is arranged and adapted to oscillate in a guide D', of wood or other suitable material, on the rod p of the pouncer-frame Q and is thereby 80 caused to move vertically with said frame, so as to always be in proper position to transmit motion to the pad-body of the pouncer S. Such motion is transmitted through the medium of a sleeve E', adjustably fixed on the 85 arm C' by a set-screw i', a sleeve F', loosely mounted on the arm and connected in a swivled manner to the sleeve E', and a pitman G', interposed between the sleeve F' and the rod n' of pouncer S and connected in a hinged 90 manner to the former and by a universal joint to the latter. The adjustable fixture of the sleeve E' on the arm C' is provided in order that the thrust or throw of the pouncer-pad may be regulated at pleasure, it being simply 95 necessary to move the sleeve E' toward the free end of the arm C' to increase the throw and in the opposite direction to diminish the same. The arm C' rocks on its axis incident to its oscillations, and the swivel connection 100 between the sleeves E' F' is provided to prevent the communication of such rocking motion to the pitman G'.

It will be appreciated that by virtue of the mechanism just described a steady working 105 movement is transmitted to the pad-body of the pouncer irrespective of its position with respect to a hat placed on the support or block D and also that said mechanism is free to accommodate itself to the movements of the T-lever 110 N, pouncer-frame Q, and pouncer S and steadily actuate the pad-body of the latter during its movements up the body and over the top of a hat, as well as in its movements toward and from the hat. It will further be appreciated that the rotary movement of the shaft 115 A', which is located at the center of movement of the T-lever N, is converted into reciprocal motion, such as is necessary to properly actuate the pad-body of the pouncer. 120

H' is a gear-case connected to the frame A, and I' is a loose band-pulley, which is held against lateral movement on the shaft C by a collar j' and has the inner end of its hub k' extended within the case H' and provided 125 with peripheral gear-teeth l' and four (more or less) notches p'.

J' is a movable device, preferably a key, which extends through a longitudinal slot q' in the shaft C and is designed when it enters 130 any one of the notches p' of the hub k' to fix the band-pulley C to said shaft and cause the two to revolve together. Said key J' is formed integral with a slide K', which is journaled

at its outer end in a connecting-rod L' , interposed between it and a hand-lever M' , pivotally mounted on the frame A .

N' is a gear-wheel or annulus, which is 5 loosely mounted on the shaft within the case H' and is provided with a flange r' , having two diametrically opposite notches s' , and P^2 is a spacing-collar, which is secured by a set-screw or other suitable means on the shaft 10 C in a position between the notched end of the pulley-hub and the flange r' of gear-wheel N' and is provided with a notch r^2 for the passage of the key J' . The gear-wheel N' meshes with a gear-wheel P' , mounted on a 15 short shaft v' , supported in one side wall of the gear-case, while the gear portion of the pulley-hub meshes with a gear-wheel Q' , mounted on a short shaft v' , supported in the other side wall of the case. In the present 20 embodiment of the invention the gear-wheels are of such proportional sizes that the wheel Q' will make one revolution to two of the pulley-hub and the gear-wheel P' will make two revolutions to one of the gear-wheel N' . 25 From this it will be appreciated that when the gear-wheel N' is fixed to shaft C through the medium of key J' and the gear-wheels Q' and P' are connected by means presently described, so as to simultaneously make one 30 revolution, the shaft C will make but one revolution incident to four revolutions of the band-pulley I' . It will also be appreciated that the shaft C and the block D will make but one revolution incident to two revolutions of the gear-wheel P' . With this understanding the following description of the differential power-transmitting means interposed between the shaft C and the pulley I' , which latter constitutes a primary driver, 35 40 will be readily comprehended.

By reference to Figs. 17 and 18 it will be seen that the gear-wheels $Q' P'$ are provided at equidistant points from their respective centers with lateral projections $Q^2 P^2$, respectively, and that the said lateral projections are connected by a link R' , which loosely receives them and is arranged between the gear-wheels $Q' P'$. It will also be observed that the axis or shaft v' of wheel Q' is off the center of wheel P' and may be moved toward and from said center by reason of it being 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 notches p' of the pulley I' , and thereby fix the pulley to the shaft and cause the shaft and its block D to rotate four times as fast as when the pouncer was operating against the sides and ends of the hat-body.

5 Coincident with the completion of the operation of the pouncer against the tip of the hat the trip K on wheel G dislodges the dog J from its seat g in the frame A , with the result that the pouncer falls away from the hat and the machine is placed out of operation.

When a round hat is to be pounced, a round block is substituted for the block D , and the shaft C is fixed to the pulley I' , so as to impart a regular and comparatively fast rotary motion to the round block from the time that the pouncer begins operations on the round hat until it drops away from the tip thereof.

10 The regular and comparatively fast motion of the shaft C , due to fixing it directly to the pulley I' , is also designed to be used to advantage in slicking both oblong and round hats subsequent to the pouncing thereof. The slicking operation is similar to the pouncing operation, with the exception that incident to the movement of the pouncer up the body and over the tip of the hat the shaft A' is idle and the pouncer-pad is not actuated. The said shaft A' may be rendered idle by 15 any suitable means—as, for instance, by removing its drive-belt.

It will be readily appreciated from the foregoing that the operator of my improved machine is enabled through the medium of the lever M' to quickly and easily change the slow and irregular rotary motion of the shaft C to a comparatively fast and regular rotary motion, or vice versa, and is also enabled to stop said shaft when desirable. It will also 20 be appreciated that the operator is enabled, through the medium of the lever L , to conveniently raise the lever E , and thereby place the pouncer-feeding mechanism in gear with the shaft C . The lever d , which, like the levers M' and L' , is placed in a position for convenient manipulation, is simply provided in order to enable the operator to quickly and easily secure hat-blocks on and remove them 25 from the shaft C .

Having thus described my invention, what I claim is—

1. In a hat-machine, the combination of a hat-support, and automatic, irregular-motion-transmitting means for driving the same, substantially as specified.

2. In a hat-machine, the combination of a primary driver, a hat-support, and an automatic, irregular-motion-transmitting driving connection for rotating the hat-support fast and slow alternately, substantially as specified.

3. In a hat-machine, the combination of a primary driver, a hat-support, an automatic, irregular-motion-transmitting driving connection for driving the hat-support fast and slow alternately, and means for coupling the hat-support to the primary driver and the said

driving connection alternately, substantially as specified.

4. In a hat-machine, the combination of a primary driver, a hat-support, differential-motion, power-transmitting means arranged to be actuated by the primary driver, and means for fixing the hat-support with respect to the primary driver and the differential-motion power-transmitting means, alternately, substantially as specified.

5. In a hat-machine, the combination of a primary driver, a hat-support, differential-motion, power-transmitting means arranged to be actuated by the primary driver, and a movable key adapted in one position to fix the hat-support with respect to the primary driver and in another position to fix said support with respect to the differential-motion power-transmitting means, substantially as specified.

6. In a hat-machine, the combination of a shaft having mounted thereon a hat-block, a pulley loose on the shaft, and differential-motion gearing between the pulley and shaft for converting the regular rotary motion of the former into an irregular rotary motion and imparting such irregular motion to the latter, substantially as specified.

7. In a hat-machine, the combination of a shaft having mounted thereon a hat-block, a pulley loose on the shaft, differential gearing connected with the pulley and adapted to be connected to the shaft, and a movable key adapted in one position to fix the pulley to the shaft and in another position to connect the differential gearing to said shaft, substantially as specified.

8. In a hat-machine, the combination of a shaft having mounted thereon a hat-block, a pulley loose on the shaft, an annular gear loose on the shaft, differential gearing interposed between the pulley and the loose, annular gear, a movable key adapted in one position to fix the pulley to the shaft and in another position to fix the annular gear to the shaft, and a handle connected to said key, substantially as specified.

9. In a hat-machine, the combination of a shaft having mounted thereon a hat-block, a pulley loose on the shaft and having gear-teeth on its hub, an annular gear loose on the shaft, gear-wheels mounted side by side on eccentric centers and intermeshed with the pulley-hub and loose, annular gear, respectively, a link interposed between and connecting the side-by-side gear-wheels, and a movable key adapted in one position to fix the pulley to the shaft and in another position to fix the loose, annular gear to said shaft, substantially as specified.

10. In a hat-machine, the combination of a hollow and slotted shaft having mounted thereon a hat-block, a pulley loose on the shaft and having a seat in its inner end, an annulus loose on the shaft and having a seat in its side adjacent to the pulley, differential power-transmitting means interposed between the

loose pulley and annulus, a key movable in the slot of the hollow shaft and adapted in one position to enter the seat of the pulley and in another position to enter the seat of the annulus, and a slide arranged within the hollow shaft and connected to the key, substantially as specified.

11. In a hat-machine, the combination of a framework, a primary driver, a hat-support, power-transmitting means arranged to be actuated by the primary driver, a movable key for fixing the hat-support with respect to the primary driver and the power-transmitting means, alternately, a hand-lever fulcrumed on the framework, and a connection between said lever and the key, substantially as specified.

12. In a hat-machine, the combination of a framework, a hollow and slotted shaft having mounted thereon a hat-block, a pulley loose on the shaft and having a seat in its inner end, an annulus loose on the shaft and having a seat in its side adjacent to the pulley, differential, power-transmitting means interposed between the loose pulley and annulus, a hand-lever pivoted on the framework, a rod connected to the hand-lever, a slide arranged in the hollow shaft and journaled in said rod, and a key connected to the slide and movable in the slot of the hollow shaft; said key being adapted in one position to enter the seat of the pulley and in another position to enter the seat of the annulus, substantially as specified.

13. In a hat-pouncing machine, the combination of a hat-support, a pouncer for operating against a hat on the support, an automatic, irregular-motion-transmitting means for driving the support whereby certain parts of a hat thereon are automatically subjected to the action of the pouncer to a greater extent than other parts thereof, substantially as specified.

14. In a hat-pouncing machine, the combination of a primary driver, a hat-support, a pouncer for operating against a hat on the support, and automatic, irregular-motion-transmitting means for driving the hat-support by the primary driver, substantially as specified.

15. In a hat-pouncing machine, the combination of a primary driver, a hat-support, a pouncer for operating against a hat on the support, differential, power-transmitting means arranged to be actuated by the primary driver, and means whereby the hat-support may be connected to the primary driver and the differential power-transmitting means, alternately, substantially as specified.

16. In a hat-pouncing machine, the combination of a shaft, automatic, irregular-motion-transmitting means for driving the same, a pouncer, and an oblong hat-block so arranged on the shaft that its flat or substantially flat sides will be presented to the pouncer incident to the slow motions of the shaft, and its rounded ends will be presented to said pouncer incident to the fast motions of the shaft, substantially as specified.

17. In a hat-pouncing machine, the combination of a shaft, automatic, irregular-motion-transmitting means for driving the same, an oblong hat-block secured on the shaft and having a socket, and a dowel-pin connected to the shaft and arranged in the socket of the hat-block; said dowel-pin being so arranged that the flat sides of the hat-block will be presented to the pouncer incident to the slow motions of the shaft, and its rounded ends will be presented to said pouncer incident to the fast motions of the shaft, substantially as specified.

18. In a hat-pouncing machine, the combination of a primary driver, a shaft having mounted thereon a hat-block, differential, power-transmitting means for driving the latter by the former, a power-transmitting wheel adapted to receive motion from said shaft, a swinging lever in which said wheel is journaled, a crank rigid on the shaft of said wheel, a series of levers connected with and actuated by said crank, and a pouncer carried by the outer of said levers, substantially as specified.

19. In a hat-pouncing machine, the combination of a primary driver, a shaft having mounted thereon a hat-block, differential, power-transmitting means arranged to be actuated by the primary driver, means for fixing the shaft with respect to the primary driver and the power-transmitting means, alternately, a power-transmitting wheel adapted to receive motion from said shaft, a swinging lever in which said wheel is journaled, a crank rigid on the shaft of said wheel, a series of levers connected with and actuated by said crank, and a pouncer carried by the outer of said levers, substantially as specified.

20. In a hat-pouncing machine, the combination of a shaft having mounted thereon a hat-block, a power-transmitting wheel adapted to receive motion from said shaft, a swinging lever in which said wheel is journaled, a crank rigid on the shaft of said wheel, a series of levers connected with and actuated by said crank, a pouncer supported by the outer of said levers, a pouncer-actuating shaft forming the main pivot of the series of levers, and a connection between said shaft and the pouncer, substantially as specified.

21. In a hat-pouncing machine, the combination of a series of levers supported by the frame of the machine, a pouncer carried by the outer of said series, a pouncer-actuating shaft forming the main pivot of the series of levers, and a driving connection between said shaft and the pouncer, substantially as specified.

22. In a hat-pouncing machine, the combination of a series of levers supported by the frame of the machine, a pouncer carried by the outer of said series, a pouncer-actuating shaft comprising an end portion forming the main pivot of the series of levers, an intermediate, enlarged portion having an outer oblique face, and an outer portion disposed at right angles to the oblique face of the en-

largement, a sleeve loosely mounted on said outer portion of the shaft and having an angular arm, and a connection between said arm of the sleeve and the pouncer, substantially as specified.

23. In a hat-pouncing machine, the combination of a series of levers supported by the frame of the machine, a pouncer carried by the outer of said series, a pouncer-actuating shaft comprising an end portion forming the main pivot of the series of levers, an intermediate, enlarged portion having an outer oblique face, and an outer portion disposed at right angles to the oblique face of the enlargement, a sleeve loosely mounted on said outer portion of the shaft and having an angular arm, a sleeve adjustably fixed on said arm, a second sleeve connected in a swiveled manner to the adjustable sleeve, and a connection between the latter sleeve and the pouncer, substantially as specified.

24. In a hat-pouncing machine, the combination of a hat-support, a pouncer for operating against a hat on the support, means for actuating the pouncer, means for moving the pouncer over the hat, and automatic, irregular-motion-transmitting means for driving the hat-support, substantially as specified.

25. In a hat-pouncing machine, the combination of a primary driver, a shaft having mounted thereon a hat-block, differential, power-transmitting means arranged to be

actuated by the primary driver, means for fixing the shaft with respect to the primary driver and the power-transmitting means, alternately, a power-transmitting wheel adapted to receive motion from said shaft, a swinging lever in which said wheel is journaled, a crank rigid on the shaft of said wheel, a series of levers connected with and actuated by said crank, a pouncer carried by the outer of said levers, a pouncer-actuating shaft forming the main pivot of the series of levers, and driving connections between said shaft and the pouncer, substantially as specified.

26. In a hat-pouncing machine, the combination of a hat-support, a pouncer for operating against a hat on the support, means for actuating the pouncer, means for moving the pouncer over the hat, differential power-transmitting means calculated to impart an irregular rotary motion to the hat-support, a primary driver, and means for fixing the hat-support with respect to the primary driver and the differential power-transmitting means, alternately, substantially as specified.

In testimony whereof I have hereunto set my hand in presence of two subscribing witnesses.
